United States Patent

Des. 239,886

Patented May 18, 1976

239,886

POCKET ATTACHABLE TO A STRAP OR SIMILAR ARTICLE

Lorraine Finch, 2106 Lapeer St.,
Flint, Mich.

Filed July 9, 1973, Ser. No. 377,555

Term of patent 14 years

Int. Cl. D2—07

U.S. Cl. D2—400

Fig-1

Fig-2

Fig-3

Fig-4

Fig-5

FIG. 1 is a front perspective view of an attachable pocket of my new design with the flap of the pocket closed;

FIG. 2 is a view similar to FIG. 1 but illustrating the flap of the pocket opened;

FIG. 3 is a view similar to FIG. 1 but illustrating the pocket in a fully expanded position;

FIG. 4 is a rear elevational view of the attachable pocket of my new design, and

FIG. 5 is a side elevational view of the attachable pocket of my new design.

I claim:

The ornamental design for a pocket attachable to a strap or similar article, as shown and described.
